(57) **CLAIM**

The ornamental design for a tape feeder, as shown and described.

DESCRIPTION

FIG. 1 is a first perspective view of a tape feeder, showing our new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a cross-sectional view thereof, taken along line 9-9 of FIG. 4;

FIG. 10 is a cross-sectional view thereof, taken along line 10-10 of FIG. 4;

FIG. 11 is an enlarged partial cross-sectional view thereof, taken along the intersection of lines 11-11 of FIG. 9;

FIG. 12 is an enlarged partial cross-sectional view thereof, taken along the intersection of lines 12-12 of FIG. 10;

FIG. 13 is an enlarged partial view thereof, taken along the intersection of lines 13-13 of FIG. 1; and,

FIG. 14 is an enlarged partial view thereof taken along the intersection of lines 14-14 of FIG. 2.

The dash broken lines in the drawings illustrate portions of the tape feeder which form no part of the claimed design. The dot-dash broken lines illustrate boundaries which form
